UNITED STATES PATENT OFFICE.

JOHN J. DRAKE, OF ELIZABETH, NEW JERSEY, ASSIGNOR TO THE SINGER MANUFACTURING COMPANY, OF ELIZABETH, NEW JERSEY, A CORPORATION OF NEW JERSEY.

GUIDE FOR SEWING MACHINES.

Application filed January 20, 1920. Serial No. 352,871.

To all whom it may concern:

Be it known that I, JOHN J. DRAKE, a citizen of the United States, residing at Elizabeth, in the county of Union and State of New Jersey, have invented certain new and useful Improvements in Guides for Sewing Machines, of which the following is a specification, reference being had therein to the accompanying drawings.

10 This invention relates to sewing machines, more particularly of the hat sewing type, and has for an object to provide a guide which will operate in conjunction with the work-supporting and work-feeding devices 15 of the machine to present a previously folded over edge portion of material, such as the brim of a hat, to the sewing instruments in such a manner that the inwardly disposed free edge of the fold will be blind 20 stitched to the body of the material, thereby forming an edge finish for the latter.

The present guide is adapted, more particularly, for use on a hat sewing machine of the type disclosed in the patent to Alfred 25 Grieb, No. 1,206,433, of Nov. 28, 1916, and comprising opposed horizontal work-feeding and presser-wheels between which is positioned a freely rotatable vertical work-supporting wheel, the top edge of which is 30 adapted to support a folded portion of a hat body while clamped between the presser and feed-wheels, so that the horizontally reciprocating needle will enter and emerge from the upper side of the material without 35 passing through to the opposite or under side thereof, thereby forming blind stitches which have heretofore been customarily employed in stitching the sweat band to position within the crown of the hat.

40 The present guide is adapted to be carried by the support for the presser-wheel and is formed with a pair of spaced downwardly extending rests or lips defining between them an inverted trough having within it 45 a groove for reception of the folded over free edge of the hat brim; the lips or rests assisting in forming a reverse fold in the material of the hat brim adjacent the said folded over free edge and presenting said 50 reverse fold and free edge to the feed- and presser-wheels in such relation that the needle will stitch through the folded over free edge and into the reverse fold adjacent thereto without passing through to the 55 under side of the material at the latter fold.

In the accompanying drawings, Fig. 1 is a side elevation of a well known type of hat sewing machine embodying the invention. Fig. 2 is a top plan view of the essential elements of the machine adjacent the stitching point. Fig. 3 is a vertical section through the feed and presser-wheels in the plane of the needle, showing the work in section. Fig. 4 is a view of the present guide and its support looking in the direction of the arrow, Fig. 2; the work and feed-wheel being removed. Fig. 5 is a side elevation of the guide. Fig. 6 is a fragmentary bottom plan view of the guide. Fig. 7 is a section on the line 7—7, Fig. 5 and Fig. 8 is a sectional view of the seam formed by a machine embodying the invention.

For the purposes of the present disclosure the invention is shown as embodied in a hat sewing machine constructed substantially in accordance with the disclosure of the said Grieb patent. A machine of this type commonly comprises a supporting frame having a base 1 and a standard 2 within which is housed suitable actuating mechanism for the horizontally reciprocating needle 3 and the looper 4; the latter operating to seize a loop of thread passed through the work by the needle and carry said loop over the folded edge of the work for entry by the needle on its next work piercing thrust, as shown in Figs. 2 and 3. The machine also comprises a feed-wheel which, in the embodiment illustrated, is constituted by the horizontally disposed, peripherally serrated wheel 5 mounted on the step-by-step moving feed-shaft 6 which receives its motion from well known driving mechanism, not shown.

Opposed to the feed-wheel 5 and cooperating with the latter to feed the work is the usual presser-wheel 7 which is mounted to turn freely upon the stud-pin 8 fixed in the lug 9 at the lower end of the depending portion 10 of the usual pivotally mounted and spring-pressed presser-arm 11 which rises from below the bed 1. The present machine further comprises a work-support in the form of a vertically disposed disk 12 mounted to turn freely upon the ball 13 carried by the bracket 14 which is mounted as usual for pivotal adjustment upon the pin 15 fixed to the presser-arm 11. The disk 12 is usually adjusted to a height such that it will support the folded portion of a hat, where 110

the crown joins the brim, so that the needle will enter and emerge from the same side of the material without passing through to the other side of the material. In other words, the disk 12 supports the work so that it will be blind stitched; these machines being commonly used for sewing in the sweat band.

In the present instance, however, a guide *g* 10 is provided which adapts the machine for the particular operation of finishing the edge of a hat brim, to be disclosed. The present guide comprises a horizontally disposed shank 16 which is secured to the usual 15 guide-supporting bracket 17 by means of the screw 18 and friction washer 19. The bracket 17 is mounted upon the lug 9 at the free end of the presser-arm and overhangs the presser-wheel 7; the overhanging 20 portion of the bracket 17 being steadied by means of a screw 20 which is threaded into the fixed pin 8.

The guide *g* is formed at its free end with a guiding head including the depending rest 25 21 for the body of the hat brim and the overhanging rest or lip 22, which rests define an inverted trough, as shown in Fig. 5. Within this trough, the guiding head is 30 formed with a shoulder 23 and a groove 24, the latter being disposed at one side of and at a higher level than the shoulder 23. Referring to Figs. 4 and 7, it will be seen 35 that the shoulder 23 is upwardly inclined toward the delivery end of the guiding head, said inclination approximating that of the adjacent portion of the periphery of the work-supporting disk 12. At the delivery end of the guide-head, as well as at the receiving end, the shoulder 23 is below the 40 level of the groove 24.

Adjustably mounted on the guide-shank 16 by means of a screw-and-slot connection 45 25 is a stop 26 which is adapted to strike the shoulder 27 on the usual adjustable loop-finger 28 common to machines of the present type, and thus determine the operative position of the guide-head relative to the needle.

Preparatory to the operation of the present device to finish the edge of a hat brim *b*, 50 it is necessary to prepare the hat by folding over and creasing the marginal portion of the hat brim, as shown at 29, Fig. 2; a pre-formed edge-fold 30 being thus provided. The free edge 31 of the hat brim is accordingly disposed inwardly from the edge-fold 29. The marginal portion of the hat brim is then introduced between the feeding and presser-wheels 5 and 7 and is bent over the work-supporting disk 12, as shown in Fig. 3, 55 thus forming a reverse fold 32 adjacent the free edge 31 and in position to be blind stitched to said free edge.

As the machine is operated, the work-support 60 12 acts in conjunction with the rests 21 and 22 to deflect or reversely bend the hat

brim into the inverted trough between said rests; the bend or fold 32 being gradually sharpened and elevated until it reaches stitching position in the condition illustrated in Fig. 3. During this bending operation, the body of the hat brim is guided by the rest 21 and the inwardly bent free edge 31 of the hat brim travels along and is confined against upward movement by the groove 24. The fold 32 travels along the inclined shoulder 23. The overhanging lip or rest 22 thus confines the initially formed fold 30 at an angle to the main body portion of the hat brim, as shown in Figs. 1 and 2. Since the shoulder 23 is below the level of the groove 24, the edge 31 will be presented to the needle somewhat higher than the fold 32, in order that the thread will be securely anchored in the fold 30.

When it is desired to use the machine for other stitching operations, the guide may be readily swung to an out of the way position, as shown in dotted lines in Fig. 2. The upwardly extending post 33 which is rigid with the shank 16 of the guide affords a convenient finger piece for shifting the guide about its pivot 18.

After the stitches 34 have been formed, the hat brim is ironed out flat, as shown in Fig. 8, wherein it will be seen that the stitches 34 are blind or invisible at the under side of the hat brim.

Having thus set forth the nature of the invention, what I claim herein is:—

1. In a hat sewing machine, the combination with stitch-forming mechanism including a horizontally reciprocating needle, and feeding mechanism including a horizontally disposed work-engaging wheel, of means including a guide having depending lip and rest elements disposed outside of the periphery of said wheel for reversely folding the marginal portion of a hat brim adjacent the inwardly disposed free edge of a pre-formed edge fold and presenting said free edge and reversely folded portion to the stitch-forming and feeding mechanisms.

2. In a hat sewing machine, the combination with a presser-wheel, of a guide comprising a depending rest extending below the plane of the upper end of the presser-wheel and outside of the periphery of such wheel for positioning the body of the hat-brim, and an overhanging lip for confining an edge-fold in angular relation to the body of the hat-brim, said guide being formed between said rest and lip with a groove for guiding the free folded over edge of the hat-brim.

3. In a hat sewing machine, in combination, a presser-wheel, a presser-wheel support, a guide-shank mounted upon the presser-wheel support, and a guide for the hat formed at the free end of said shank

and comprising a lip and a depending rest extending below the plane of the upper end of the presser-wheel and outside of the periphery of such wheel for positioning the body of the hat-brim, said guide being formed between said rest and lip with a groove for guiding the free folded over edge of the hat-brim.

4. A guide for hat sewing machines comprising, opposed depending rests defining an inverted trough, said guide being formed within the trough with a shoulder and with a groove at one side of and above the level of said shoulder, substantially as and for the purpose specified.

5. In a hat sewing machine, the combination with stitch-forming mechanism including a horizontally reciprocating needle and feeding mechanism including opposed feeding and presser-wheels, of means in advance of said stitch-forming and feeding mechanisms and between said wheels for reversely folding the marginal portion of a hat brim adjacent the inwardly disposed free edge of a pre-formed edge fold and presenting said free edge and reversely folded portion to the stitch-forming and feeding mechanisms.

6. In a hat sewing machine, the combination with stitch-forming mechanism including a horizontally reciprocating needle, feeding mechanism including opposed horizontal feeding and presser-wheels, and a work-support operating between said wheels, of guiding means disposed between said wheels and acting in conjunction with said work-support to reversely fold the marginal portion of a hat brim adjacent the inwardly disposed free edge of a pre-formed edge fold and present said free edge and reversely folded portion to the stitch-forming and feeding mechanisms.

7. In a hat sewing machine, the combination with stitch-forming mechanism including a horizontally reciprocating needle, feeding mechanism including opposed horizontal feeding and presser-wheels, and a vertically disposed work-supporting disk between said wheels, of guiding means disposed between said wheels and acting in conjunction with said disk to reversely fold the marginal portion of a hat brim adjacent the inwardly disposed free edge of a pre-formed edge fold and present said free edge and reversely folded portion to the stitch-forming and feeding mechanisms.

8. In a hat sewing machine, the combination with stitch-forming mechanism including a horizontally reciprocating needle, and

feeding mechanism including opposed feeding and presser-wheels, of a guide disposed in advance of said stitch-forming and feeding mechanisms and comprising a depending rest between said wheels for positioning the body of a hat brim, and an overhanging lip between said wheels for confining and guiding a pre-formed edge fold to the stitch-forming mechanism in angular relation to the body of the hat brim.

9. In a hat sewing machine, the combination with stitch-forming mechanism including a horizontally reciprocating needle, and feeding mechanism including opposed feeding and presser-wheels, of a guide disposed in advance of said stitch-forming and feeding mechanisms and comprising a depending rest between said wheels for positioning the body of a hat brim, and an overhanging lip between said wheels for confining and guiding a pre-formed edge fold to the stitch-forming mechanism in angular relation to the body of the hat brim, said guide being formed between said depending rest and overhanging lip with a groove for guiding and confining the free edge of the pre-formed edge fold.

10. In a hat sewing machine, the combination with stitch-forming mechanism including a horizontally reciprocating needle and feeding mechanism including a horizontal wheel, of a guide comprising opposed rests located outside of the periphery of said wheel and depending below the plane of the upper edge of said wheel, thereby defining an inverted trough, and means cooperating with said guide to bend the marginal portion of a hat brim upwardly into said trough during the operation of the machine and present the folded work to the stitch-forming and feeding mechanisms.

11. In a hat sewing machine, the combination with stitch-forming mechanism including a horizontally reciprocating needle and feeding mechanism including opposed horizontal wheels, of a guide comprising opposed depending rests disposed between said wheels and defining an inverted trough, and a work-supporting wheel turning upon a substantially horizontal axis and cooperating with said guide to bend the marginal portion of a hat brim upwardly into said trough during the operation of the machine and present the folded work to the stitch-forming and feeding mechanisms.

In testimony whereof, I have signed my name to this specification.

JOHN J. DRAKE.
